UNITED STATES PATENT OFFICE

ROBERT F. REICH, OF TRYON, NORTH CAROLINA

ANTIDRIFTING ATTACHMENT FOR AUTOMOBILES

Application filed November 3, 1928. Serial No. 317,010.

The present invention relates to attachments for automobiles and similar motor driven vehicles and has for its principal object to provide means operatively connected with the 5 drive mechanism for preventing drifting movement of the vehicle while standing in a forwardly or rearwardly inclined position.

An important object of the invention resides in the provision of means operatively 10 connected with the drive shaft of the vehicle for securing the same against drifting movement while standing in an inclined position and while the motor is running whereby to permit the operator to release the brake of 15 the vehicle in advance of letting in the clutch and thus permit the vehicle to be driven upwardly of the inclined surface from a standing position.

A further important object of the invention 20 is to provide an attachment of this character which is automatic in its operation and equally well adapted for driving the vehicle in either a forward or rearward direction.

An additional object is to provide an attachment of this character which is automatic 25 in its operation, which embodies efficiency and simplicity in its construction, which is strong and durable, which may be installed in operative position upon the drive mechanism of the 30 vehicle without necessitating any material changes or alterations in the construction thereof and is otherwise well adapted for the purposes for which the same is intended.

Other objects and advantages reside in 35 the special construction, combination and arrangement of the various elements forming the invention as more fully hereinafter described and claimed, reference being had to 40 the accompanying drawings forming part hereof, wherein like numerals refer to like parts throughout, and in which:

Figure 1 is a side elevational view of the transmission and clutch mechanism of a motor driven vehicle with the device, constitut-

ing the subject matter of my invention, shown in operative position with respect thereto,

Figure 2 is a perspective view of the specially constructed drive shaft with which the invention is operatively connected,

Figure 3 is a transverse sectional view through the shaft showing the gears, forming part of the invention, operatively connected therewith,

Figure 4 is a similar view of the reverse side 55 of said gear,

Figure 5 is a vertical sectional view through said gears and the pawl and ratchet mechanism operatively associated therewith.

Figure 6 is a plan view of the idler gear 60 illustrating the friction locking means for the hub thereof, and

Figure 7 is a perspective view of the pawl.

Referring now to the drawings in detail, for the purpose of illustration I have disclosed 65 my invention mounted in operative position with respect to a vehicle transmission mechanism indicated generally at 5 and clutch mechanism 6 for controlling the operation of the drive shaft 7.

The transmission and clutch mechanism are shown operatively mounted in housings 8 and 9 respectively, in a manner well known in the art, the clutch housing 9 having a vertically extending support 10 arranged therein and provided with an opening through which the forward end of the drive shaft 7 is journaled and also provided with an opening for rotatably supporting one end of a sub-shaft 11 disposed in parallel relation above 80 the drive shaft 7 and with its rear end journaled in the rear section of the housing 12.

The portion of the drive shaft disposed immediately beneath the sub-shaft 11 is square shaped in cross section, as illustrated at 13, 85 the rear end of the squared portion of the shaft terminating in a flange 14. A spur gear 15 and ratchet gear 16 are mounted on the square portion of the shaft for rotation therewith and secured in position by a collar 90

17 carried on the shaft and retained in position by a set screw 18.

5 A pawl 19 is mounted for rotary movement upon the stub shaft 11 with one end 20 disposed in position for engagement with the teeth 21 of the ratchet wheel, said pawl having a square shaped hub 22 formed on one side thereof, the hub and the pawl being formed with an opening 23 for receiving the 10 shaft 11.

15 A spider 24 is mounted upon the hub 22 for rotary movement with the hub, said spider being provided with radially extending arms 25 having their outer ends arcuately formed and fitted against the inner periphery of a ring 26 for relative rotary movement with respect thereto.

20 A ring gear 27 is formed about the ring 26 and disposed in engagement with the gear 15. The spider 24 is secured against relative longitudinal movement on the hub 22 by means of bolts 28 extending through the spider and engaging the pawl 19.

25 As clearly illustrated in Figure 6 of the drawing, one edge of each of the radial arms 25 of the spider is disposed in a plane forming a chord of the inner periphery of the ring 26 as indicated at 30 whereby to form a series of recesses 31 about the edge of the spider, reduced gradually at one end by the curvature of the ring.

30 Rollers 32 are mounted within each of the recesses having their axes disposed parallel with the axis of the ring and with the surface 35 face of each of the rollers yieldably retained in frictional engagement between the tangential edge of the spider and the ring by a plunger 33 having one end slidably disposed in a recess formed in the adjacent arm 25 and normally urged outwardly against the roller by an expansion spring 34 arranged in said recess.

35 The rollers 32 are retained in assembled position by means of a cover plate 35 secured at one side of the gear 27 by the bolt 28 as clearly illustrated in Figure 5 of the drawing. A spacing member 36 is interposed between the cover plate 35 and the support 10. It will be readily appreciated from the foregoing that the ring gear 27 is permitted to rotate freely about the spider and hub in one direction, but upon the rotation of said gear in an opposite direction, the rollers 32 will be wedged between the ring 26 and the tangential edge 30 of the arms of the spider and thus prevent rotation of said ring gear.

40 A block 37 is secured inwardly of the rear end wall of the clutch housing 9 within which the rear end of the sub-shaft 11 is journaled, said block 37 having a stop pin 38 extending forwardly therefrom and engageable at one side by a stop pin 39 depending from the pawl 19 at the center thereof.

45 The end of the pawl 19, opposite from its ratchet gear engaging end 20, is provided

5 with a weighted end 40 whereby to normally retain the end 20 out of engagement with said ratchet gear. The stop pins 38 and 39 are disposed in position for engagement with each other whereby to limit the downward movement of the weighted end of the pawl beyond a position for maintaining the end 20 of said pawl just out of engagement with the ratchet gear.

70 The pawl and ring gear roller assembly are mounted in position with respect to the gears 15 and 16 so that the rotation of the drive shaft 7 during the normal operation of the car will enable the ring gear 27 to rotate idly about the spider with the pawl out of engaged position. Should the vehicle be brought to a stop and headed downwardly upon an inclined surface, through the use of the vehicle brake and with the clutch 9 thrown out of engagement, as is customary, the car may be prevented from forward driving movement by throwing the gear shift mechanism into reverse, whereby to cause a reverse movement in the drive shaft 7 forwardly of the transmission and prevent any forward drifting tendency of the car.

75 This reverse movement of the portion of the drive shaft 7 upon which the gears 15 and 16 are mounted will cause a reverse movement in the ring gear 27 from its normal direction of rotation and thus cause the wedging action of the roller 32 carried thereby. Such wedging action will create a limited rotary movement of the hub 22 causing an engagement of the end 20 of the pawl with the ratchet gear 16 thereby locking the gears 15 and 16 against further rotary movement in a reverse direction of the shaft 7.

80 The vehicle is thus securely held against forward shifting movement while permitting the operator to release the brakes of the vehicle. It is to be understood that during this operation the clutch mechanism is held out of engagement.

85 Under reverse conditions where the vehicle is brought to a stop on an upwardly inclined surface, rearward drifting movement is prevented providing the gear shift mechanism is retained in either of its forward positions while the clutch is held out of engagement, any reverse movement in the drive shaft 7 through the tendency of the car to drift rearwardly operating to reverse the direction of idle rotation of the gear 27 and cause a wedging action of the rollers 32 and thus move 110 the pawl and ratchet into locking engagement.

90 The operator is then at liberty to release the brake mechanism and the car will be held against the rearward movement until the clutch is let back into engagement for moving the car forwardly.

95 If desired a lubricating system may be provided for the rollers 32 comprising a grease channel 41 formed in the sub-shaft 11 130

with a grease nipple 42 attached at one end thereof, the inner end of the grease channel 41 terminating in a transverse passage 43 communicating with an annular groove 44 formed within the bore of the hub 22.

5 Radially extending ducts 45 extend from the channel 44 through the edges of the arm 25 of the spider in position for supplying grease to the rollers.

10 It is obvious that my invention is susceptible to various changes and modifications in construction without departing from the spirit of the invention or the scope of the appended claims, and I accordingly claim all 15 such forms of the device to which I am entitled.

Having thus described my invention, what I claim as new is:

1. A device of the class described comprising a driven shaft normally rotating in one direction, a plurality of gears mounted thereon for rotation therewith, an idler gear operatively engaged with one of said shaft gears and adapted for free rotary movement during the normal rotation of the shaft and gear locking means operatively associated with said idler gear and engageable with the other of said shaft gears and operable upon an initial reverse movement of the shaft whereby to prevent retrograde movement thereof.

20 2. A device of the class described comprising a driven shaft normally rotating in one direction, a plurality of gears carried thereby for rotation therewith, an idler gear operatively associated with one of said gears and arranged for free rotary movement upon the normal operation of the shaft, gear retaining means arranged in position for engagement with the other of said shaft gears and normally disengaged therefrom and means operatively connecting said idler gear with said gear retaining means for moving the same into gear engaging position upon an initial reverse movement of said shaft whereby to prevent retrograde movement thereof.

25 3. A device of the class described comprising a driven shaft normally rotating in one direction, a plurality of gears carried thereby for rotation therewith, an idler gear operatively associated with one of said gears and arranged for free rotary movement upon the normal operation of the shaft, gear retaining means arranged in position for engagement with the other of said shaft gears and normally disengaged therefrom and means operatively connecting said idler gear with said gear retaining means for moving the same into gear engaging position upon an initial reverse movement of said shaft whereby to prevent retrograde movement thereof, said last named means comprising wedge members operatively associated with said idler gear.

30 4. A device of the class described, com-

prising a driven shaft normally rotating in one direction, a plurality of gears carried thereby for rotation therewith, an idler gear operatively associated with one of said gears and arranged for free rotary movement upon

70 the normal operation of the shaft, gear retaining means arranged in position for engagement with the other of said shaft gears and normally disengaged therefrom and means operatively connecting said idler gear with said gear retaining means for moving the same into gear engaging position upon an initial reverse movement of said shaft

75 whereby to prevent retrograde movement thereof, said last named means comprising a plurality of wedge members disposed in concentric relation with respect to the axis of said idler gear and retained in position against rotary movement with said gear.

80 5. A device of the class described comprising a driven shaft normally rotating in one direction, a plurality of gears mounted for rotation with said shaft, an idler gear arranged in engagement with one of said

85 shaft gears, a spider providing a mounting for said idler gear, means engageable with the spider retaining the same against rotary movement with said idler gear, said means being adapted for movement into engagement with the other of said shaft gears

90 whereby to prevent the shaft against rotation in a reverse direction and a plurality of wedge members interposed between the spider and said idler gear and arranged for movement into wedging position upon an initial reverse movement of said idler gear.

95 6. A device for preventing retrograde movement comprising in combination, a driven shaft normally rotating in one direction, a plurality of gears mounted for rotation therewith, an idler gear arranged with one of said shaft gears, a pawl arranged for engagement with the other of said shaft gears,

100 a spider carried by said pawl and providing a mounting for said idler gear, said spider including a plurality of radially disposed arms having one edge thereof disposed tangentially with respect to said idler gear and a plurality of rollers disposed concentrically with respect to the axis of said idler

105 gear and arranged in wedging relation between the tangential edge of the spider and said gear for movement into wedging position upon an initial reverse movement of said shaft.

110 7. A device for preventing retrograde movement comprising in combination, a driven shaft normally rotating in one direction, a plurality of gears mounted on said shaft for rotation therewith, a sub-shaft disposed parallel with said first named shaft,

115 a pawl pivotally mounted on said sub-shaft and disposed for engagement with one of said shaft gears whereby to retain the same

120 against reverse movement of the shaft, a hub

125
